UNITED STATES PATENT OFFICE.

JOHN MURRAY, OF EDINBURGH, SCOTLAND.

PAPER-FASTENING DEVICE.

1,279,483.

Specification of Letters Patent. Patented Sept. 17, 1918.

Application filed December 3, 1917. Serial No. 205,208.

To all whom it may concern:

Be it known that I, JOHN MURRAY, a subject of the King of Great Britain and Ireland, and a resident of Edinburgh, Scotland, 5 have invented certain new and useful Improvements in Paper-Fastening Devices, of which the following is the specification.

The invention has for its object to provide simple and effective means for securing together temporarily or otherwise loose sheets 10 of letterpress or the like by way of apertures pierced in the sheets and such as to maintain alinement of the sheets and also permit of the securing of them together or 15 of the securing upon them of a temporary cover. The improved devices are of particular advantage as a means for the preliminary securing of the pamphlets or parts in connection with the loose-leaf binder which 20 forms the subject-matter of my prior Patent No. 1,243,544.

A fastening device made according to the invention comprises a tubular body part adapted to fit within the apertures (of which 25 there are of course two or more) in the sheets, and lug parts extending preferably diametrically and axially from the ends thereof—which lug parts are finally folded over upon the sheets having first been pressed 30 through the temporary cover—if there be such. The lugged tubular fastener is formed from a rectangular blank of thin sheet metal or other suitable material the width of which is substantially equal to the thickness 35 of the block of sheets it is desired to secure, while its length is approximately equal jointly to the circumference and diameter of the apertures in the sheets. At one end and at opposite sides of this rectangular blank 40 there outstand the lugs before referred to, which lugs are rather less in width than the diameter of the apertures and are of a length adequate for convenient folding over. The blank, thus of T-form is preferably 45 punched from a strip or ribbon.

In the accompanying sheet of explanatory drawings Figure 1 is a plan and Fig. 2 a side elevation showing the blank from which the improved fastener is formed, Fig. 3 being an elevation and Fig. 4 a plan of the completed fastener, all the views being on an enlarged scale.

As shown in Figs. 3 and 4 of the drawings the improved fastener comprises a tubular body part A adapted to fit within each aper-

ture in a series of loose leaves, and lug parts B, C extending diametrically and axially from the ends thereof. These lug parts are finally folded over upon the sheets, having first been pressed through the temporary cover, if 60 there be such.

As shown in Figs. 1 and 2 this improved tubular fastener is formed from a rectangular blank D of thin sheet metal or other suitable material. The width of this blank 65 is substantially equal to the thickness of the block of sheets it is desired to secure, while its length is approximately equal jointly to the circumference and diameter of the aperture in the sheets. At one end and at opposite sides of this rectangular blank D there outstand the lugs B, C, hereinbefore referred to. These lugs are rather less in width than the diameter of the aperture and are of a length adequate for convenient folding over. 70

It will be seen that the improved fastener very effectively binds together a series of loose leaves, and it may be a cover, in such wise that while cover and leaves may be readily removed the whole can be freely 80 handled without fear of their inadvertent detachment.

What I claim is:—

1. A fastener of the type described comprising a tubular body having lugs projecting from the ends thereof. 85

2. A fastener of the type described comprising a tubular body having lugs projecting axially from the ends thereof, and substantially corresponding in width to the diameter of the tubular body. 90

3. A fastener of the type described comprising a tubular body with internal web projecting beyond the ends of the tubular body to form lugs for the purpose specified. 95

4. A blank for a fastener of the type described comprising a generally rectangular sheet metal blank having at one end laterally projecting lugs, the width of said lugs corresponding substantially to the diameter 100 of a cylinder rolled from the portion of the blank extending beyond said lugs.

In testimony whereof I have signed my name to this specification, in the presence of two subscribing witnesses.

JOHN MURRAY.

Witnesses:

DAVID FERGUSON,
WILFRED HUNT.
